UNITED STATES PATENT OFFICE

2,273,896

RECIPROCATING PUMP

Frederick Richard Simms, London, and Bertram Charles Joy, Bognor Regis, England

Application May 6, 1946, Serial No. 333,678
In Great Britain July 14, 1939

8 Claims. (Cl. 103—75)

This invention is for improvements in or relating to reciprocating pumps for dealing with liquids and has for its object the provision of such a pump which while possessing the simple characteristics of a diaphragm pump is distinguished from the usual forms thereof in that both the inlet and the outlet of the pump are open in the sense of being devoid of valves. As is known, valves, whether in the inlet or the outlet of the diaphragm pump, tend to complicate the construction and cause restriction of liquid flow through the pump, giving rise to "slip." Also, in the course of time, valves in these pumps are liable, owing to wear, to reduce the efficiency of the pump. Furthermore, with the valveless diaphragm pump of this invention, no reversal of flow takes place and delivery of liquid from the pump is continuous.

According to the present invention there is provided a diaphragm pump for dealing with liquids, comprising a pump chamber having an inlet and an outlet for liquid in the wall of the chamber which are both free in the sense of being devoid of valves, a diaphragm extending substantially across the pump chamber between the inlet and the outlet, which diaphragm is reciprocatable in a direction transverse to its general plane and has at its periphery a flexible portion which is free and is arranged, in conjunction with a seating provided to cooperate with it on the wall of the chamber, to serve, by sealing with the seating during the suction stroke of the diaphragm and moving away from it under the pressure of flow of the liquid through the pump during the return stroke, as the valve means of the pump, the pump being otherwise valveless and being designed to operate under conditions involving a sufficient mass and velocity of liquid flowing to and/or from the pump chamber by way of a supply pipe and/or (as the case may be) a delivery pipe for the liquid to provide the pressure of flow referred to, and means for reciprocating the diaphragm.

Therefore, the pump which is provided by this invention is a valveless, diaphragm pump and, as will be appreciated, it is only capable of dealing with liquids, that is, substantially incompressible fluids, since its action is dependent on a sufficient pressure of flow of the liquid through the pump, derived from the kinetic energy of the flowing liquid therein, to open, and maintain open, the space between the seating and the flexible portion of the diaphragm during the whole of the return (non-suction) stroke thereof, thus dispensing with the need of valves in the pump.

Only a liquid, of course, would possess the necessary mass, or be sufficiently incompressible, to give this effect.

Further, according to the present invention, there is provided a reciprocating pump which comprises, in combination, a chamber having an inlet and an outlet, at least one flexible diaphragm movable between said inlet and outlet and means operable solely by the pressure created by the movement of the diaphragm for effecting communication between the inlet side of the diaphragm and the outlet side thereof when the diaphragm is moving in one direction and for sealing the inlet and outlet sides of the diaphragm from one another when the diaphragm is moving in the reverse direction.

The invention will be more particularly described with reference to the accompanying drawings, in which:

Figures 1, 2, 3 and 4 illustrate a suitable structure for carrying the invention into effect, and in which the diaphragm is indicated in four distinct positions wherein,

Figure 1 shows the diaphragm at the commencement of the upstroke,

Figure 2 shows the diaphragm at the mid-stroke position of the up stroke,

Figure 3 shows the diaphragm at the mid-stroke position of the down stroke and,

Figure 4 shows the diaphragm at the termination of the down stroke.

Figure 5 illustrates a pump constructed according to the present invention and suitable for the delivery of fuel to a petrol engine float chamber and in which the diaphragm is operated by a cam against the action of a spring.

Figure 6 is an end view of Figure 5.

Figure 7 illustrates a cam operable to produce a quick transfer period and a prolonged suction and delivery period.

Figure 8 illustrates a manually operated pump constructed in accordance with the present invention.

Figure 9 illustrates a pump constructed in accordance with the present invention in which both the plates partially supporting the diaphragm and the interior of the pump are given a stream line effect in order to ensure an easy passage of a liquid through the pump.

Figures 10 and 10A are fragmentary sectional views showing a portion of a pump chamber including means for effectively controlling the free edge of the diaphragm.

Figure 11 illustrates a double chamber pump

constructed in accordance with the present invention.

Figures 12 and 13 illustrate two forms of pumps each having two diaphragms arranged to ensure a perfect seal between the inlet and outlet sides of the pumps.

Figures 14, 14A, 15, 16, 17, 18, 18A, 19, 20 and 20A illustrate various types of diaphragms which can be employed in connection with the present invention.

Figures 14 and 18 being fragmentary plan views, Figures 14A, 15, 16, 17, 18, 18A, 19 and 20A being sectional views, and

Figure 20 being a plan view.

Figure 21 illustrates a pump intended for use with large volumes of liquid, which pump is provided with a series of diaphragms acting simultaneously to pump liquid from the inlet to the outlet side of the pump.

Figure 22 is a sectional view on the line 22-22 of Figure 21, showing the use of sector-shaped diaphragms and sector-shaped coating ports in that form of the invention illustrated in Figure 21.

Figure 22A is a sectional view also taken on line 22-22 of Figure 21, showing the use of circular or disc-like diaphragms and circular coating ports in that form of the invention illustrated in Figure 21, and

Figures 23 and 23A are fragmentary sectional views illustrating a curved seating for the periphery of the diaphragm which has been found to give very satisfactory results, these two figures showing the diaphragm in two positions.

In Figures 1, 2, 3 and 4 of the drawings, there is illustrated a pump in its simplest form, which pump comprises a pump chamber 1 built up of two half sections 2 and 3, the section 3, hereinafter termed "the suction section," having a centrally arranged inlet 4 connected to a supply pipe 5, whilst the section 2, hereinafter termed the "outlet section," has a central guide 6 arranged to receive a spindle 7 operable to reciprocate in the said guide and also an outlet 8 to which is connected a discharge or delivery pipe 9. Mounted upon the spindle 7 is a flexible diaphragm 10 which is maintained rigid for a predetermined portion of its area by plates 11 and 12 placed on either side thereof, whilst the periphery 13 of the diaphragm is free to yield in a direction transverse to the plane thereof. The periphery 13 of the diaphragm 10 is not secured to a casing as is usual but is free and is arranged to engage with a shoulder or seating 14 provided upon the "suction section" 3 of the pump chamber 1 so as to form a seal therewith.

The operation of the pump is believed to be as follows:

Assuming both sections 2 and 3 of the pump chamber 1 and the pipes 5 and 9 to be filled with liquid and assuming the diaphragm 10 to be in its lowest position as indicated in Figure 1, then upward movement of the diaphragm and its attached parts 7, 11 and 12 to, say, a mid-stroke position as indicated in Figure 2, will cause liquid to be drawn up the supply pipe 5 into the "suction section" 3 and, at the same time, will cause liquid contained in the "outlet section" 2 to be forced into the delivery pipe 9. Meanwhile the periphery of the diaphragm 10 will be pressed on to the seating 14 by the pressure in the "outlet section" 2 due to the prevailing head of liquid and by the negative pressure in the "suction section" 3 due to the suction head. In this manner a liquid seal is formed. These conditions prevail

until the termination of the up-stroke at which period a considerable velocity has been imparted to the columns of liquid in both the suction pipe 5 and the delivery pipe 9. Thus, as soon as the diaphragm and its attached parts commences to descend on a down-stroke, not only by this action is liquid transferred from the "suction section" 3 to the "outlet section" 2 past the flexible edge of the diaphragm, but the kinetic energy of the liquid in the supply pipe—temporarily converted to pressure energy—assisted by the action of the liquid in the delivery pipe, which tends to evacuate the "outlet section" 2, causes a further flow of liquid from the "suction section" to the "outlet section." These operations are assisted by the large transfer passage provided by the separation of the diaphragm edge from its seating, which passage may have an area many times greater than the area of the suction or discharge pipe. It will be noted that in the construction of that form of our present invention illustrated in Figs. 1 to 4 inclusive, as well as in all other forms illustrated and described herein, the position of the seating 14 between the "outlet" and "suction" chambers 2 and 3, respectively, and the length of the upward and downward strokes imparted to the diaphragm 10, are such that the central portion of the diaphragm 10 is moved to positions both above and below the plane of said seating 14.

Figure 3 indicates approximately the position of the diaphragm and the flow of liquid at about mid-stroke position of the down-stroke, the diaphragm continuing to permit the passage of liquid until the termination of the down-stroke as shown in Figure 4 and on the commencement of the up-stroke—Figure 1—when the diaphragm immediately falls on to its seating, partly by the resistance of the liquid above it and partly by the vacuous tendency beneath it brought about by an upward movement of the diaphragm plates, as well as by the natural elasticity of the diaphragm itself which tends to assume its normal flat shape.

It will be realised that at suitable speed of reciprocation of the moving parts, the flow of liquid in the discharge pipe is substantially, if not absolutely, continuous and also that the diaphragm forms an excellent liquid seal against leakage when the pump is standing idle.

Thus, it will be apparent that according to the construction outlined in Figures 1, 2, 3 and 4, there is provided a pump in which valves controlling the inlet and outlet thereof may be eliminated and in which the passage of the liquid from the inlet side of the diaphragm to the outlet side thereof is controlled by the flexible periphery of the said diaphragm so that with the exception of the reciprocatable diaphragm, it is not essential to the operation of the pump to provide it with any other movable members, which fact renders the manufacture of the pump a simple and inexpensive procedure which lends itself, when desirable, to the employment of artificial resins.

Referring to Figures 5 and 6, like numerals indicate like parts to those indicated in Figures 1, 2, 3 and 4, but it will be observed that the spindle 7 is operated by an eccentric 15 carried upon a rotatable shaft 16, the eccentric being arranged to engage with a pivoted lever 17 which bears upon the free end 18 of the spindle 7. The eccentric 15 is arranged to move the spindle 7 against the action of a spring 19 which is disposed between a shoulder 20 on the pump cham-

ber and a shoulder 21 on the spindle 7. The principle of the pump illustrated in Figures 5 and 6 is generally the same as that given in respect of the pumps illustrated in Figures 1, 2, 3 and 4, except insofar as the spring 19 effects the delivery and suction stroke. Any resistance in the delivery pipe, such as would be due to restriction past the needle valve of a float chamber, operates against the action of the spring and automatically diminishes the stroke of the pump.

Figure 7 illustrates a cam for operating the spindle 7 of the pump illustrated in Figures 5 and 6, by means of which the suction and delivery period is arranged to occupy three-quarters of each revolution of the shaft 16 whilst the period of the transfer of liquid from the inlet to the outlet side of the diaphragm occupies one-quarter of the complete revolution of the shaft.

Referring to Figure 8, there is illustrated therein a pump operating on exactly the same principle as the pump illustrated in Figures 1, 2, 3 and 4, but in the form of the invention illustrated in Figure 8 the spindle 7 is arranged to be operated by a hand lever 22 pivotally connected in a yoke 23 formed on the free end of the spindle. The lever 22 is arranged to fulcrum on a link 24 pivotally connected to a lug 25 formed on the pump chamber 1.

Figure 9 illustrates a pump constructed in accordance with the present invention in which the interior of the pump chamber and the plates 11 and 12 of the diaphragm are given a streamline contour in order to offer a minimum of resistance to the passage of a liquid through the pump.

Figures 10 and 10A are two fragmentary sectional views of a portion of a pump chamber designed for use in connection with the present invention and in which radially disposed ribs 26 are arranged to extend into the outlet section 3 of the pump chamber 1 so as to limit the upward movement of the periphery 13 of the diaphragm 10 without restricting the flow.

Figure 11 illustrates a double-chamber pump in which two diaphragms are arranged on the same spindle but in planes parallel to one another and are operable in two distinct pump chambers arranged side by side, each chamber having its own suction and delivery pipe. Such a pump may be utilised for dealing with two liquids of different character or for pumping liquid under different suction and delivery heads at the same time.

Figures 12 and 13 illustrate pumps constructed in accordance with the present invention in which two diaphragms are arranged in planes parallel to one another and are disposed in the same pump chamber. The diaphragms are operable simultaneously to pump liquid from the same inlet and out of the same outlet, the purpose of the two diaphragms being to ensure a perfect seal between the peripheries 13 and the shoulders 14 when the pump is idle and the diaphragms are in the position in which communication between the inlet and outlet sides of the diaphragms is sealed. In this construction, if one diaphragm suffers damage, the other is still available for use.

Figures 14, 14A, 15, 16, 17, 18, 18A, 19, 20 and 20A illustrate various constructions of diaphragms which can be employed with pumps constructed in accordance with the present invention.

Figures 14 and 14A illustrate a diaphragm hav-

ing a thin flexible edge to assist the transfer of the liquid pumped.

Figure 15 illustrates a diaphragm having a beaded edge and canvas insertion.

Figure 16 illustrates a diaphragm which is dished so as to increase flexibility.

Figure 17 illustrates a diaphragm having two parallel peripheries, such a diaphragm being capable of employment with the pump illustrated in Figure 13.

Figures 18 and 18A illustrate a diaphragm consisting of two rubber discs 28 and 29 vulcanised to a spring steel disc 30 having radial slots 31 formed therein so as to add to the flexibility of the outer portions of the diaphragm, such a diaphragm being of particular utility in cases where high pressures are involved.

Figure 19 illustrates a diaphragm with a vulcanite or metal centre 32 and an outer rubber portion 33 vulcanised to the centre, such a diaphragm requiring no backing plates and being of cheap construction. If necessary, the diaphragm can be made of rubber throughout but wherein the flexibility increases from substantial rigidity at the centre to the desired flexibility at the periphery.

Figures 20 and 20A illustrate a diaphragm which is oval in shape and which may be used in a pump which has to be employed in a narrow elongated space. All the diaphragm or any parts thereof previously described may be provided with canvas insertions or strengthened with woven wire or may be strengthened in any desired way, for example, by sheet metal or the like or by the flexible portion of the diaphragm being vulcanised upon a suitable harder material dependent upon the liquid which is to be dealt with, it being generally understood that the lower the viscosity of the liquid employed the stiffer must be the diaphragm. Although the peripheries of the diaphragm illustrated are shown as being continuous, it is to be understood that a series of radial slots may be formed at the periphery so as to lessen the non-sealing effect of any obstruction which may occur between the periphery of the diaphragm and the seating therefor.

Figure 21 illustrates a pump in which a series of diaphragms is arranged in the same plane on a "deck" so as to engage at their peripheries 13 with shoulders 14 formed around the peripheries of holes formed in a plate which extends between a common outlet section 2 and a common suction section 3 of the pump chamber, the aforesaid deck forming part of a common suction section. The diaphragms are connected by a spider 27 to a single spindle 1 extending through a guide 6 in the outlet section 2 of the pump chamber. The spindle is arranged to be operated in any desired manner.

In Figures 22 and 22A of the accompanying drawings, the diaphragms and their co-acting ports are for the reason of space economy shown sector-shaped as in Figure 22, but the said diaphragms and their coacting ports may be circular as illustrated in Fig. 22A.

It must be stated that in the case of all the pumps described the seating provided for the diaphragm must be rendered very smooth so that the diaphragm may slide freely thereon when the pump is working, and that in all of the pump constructions described and illustrated herein, the position of the seating 14 between the "outlet" and "suction" chambers, and the length of the upward and downward strokes imparted to

the diaphragm 10, are such that the central portion of the diaphragm 10 is moved to positions both above and below the plane of said seating 14.

It will be appreciated by any one skilled in the art that in the case of the inlets and outlets of the various pumps described, as well as in the length of either the suction or delivery pipe, or of both, the dimensions must be controlled so as to allow the kinetic energy of the liquid in the pump and pipe system to assist the cycle of operation of the pump to be carried out effectively in the manner described, but such matters are questions of design, as is also the ratio of the lift of the diaphragm to the size of the discharge passage between the inlet and outlet sides of the diaphragm. Thus it is to be understood that the structure of the pump may be such as to include a passage, for example, a spiral or helical passage, long enough to hold a column, or part of a column, of liquid sufficient to ensure, in all circumstances, that the necessary kinetic energy is produced to effect the efficient operation of the pump.

What we claim as our invention and desire to secure by Letters Patent of the United States is:

1. A pump for liquids comprising a pump casing, a pump chamber within said casing having spaced inlet and outlet passages, said passages being devoid of valves; a seating within said chamber between said inlet and outlet passages; a reciprocable diaphragm within said chamber between said inlet and outlet passages acting as a combined piston and valve and dividing the pump chamber into a suction section in communication with the inlet passage and an outlet section in communication with the outlet passage, said diaphragm having a central portion and a free and flexible peripheral portion, said peripheral portion adapted to engage said seating during the power stroke of the diaphragm when the diaphragm is drawing liquid into the suction section through the inlet passage and simultaneously forcing liquid from the outlet section through the outlet passage, and to move away from said seating during the return stroke of the diaphragm under the pressure of the flow of the liquid through the pump to permit passage of the liquid from said suction section to said outlet section; and means for reciprocating said diaphragm, the position of said seating with respect to the suction and outlet chambers, as well as the length of the reciprocating movements imparted to the diaphragm, being such that the central portion of said diaphragm is moved to positions both above and below said seating as said diaphragm is reciprocated.

2. A pump for liquids as defined in claim 1 wherein the inlet passage is of sufficient length to insure, by the kinetic energy of the liquid flowing through said passage, the necessary pressure of flow of liquid upon the free and flexible portion of the diaphragm during the return stroke of the diaphragm to cause the said free and flexible portion to move away from the seating.

3. A pump for liquids as defined in claim 1 wherein the outlet passage is of sufficient length to insure, by the kinetic energy of the liquid flowing through said passage, the necessary pressure of flow of liquid upon the free and flexible portion of the diaphragm during the return stroke of the diaphragm to cause the said free and flexible portion to move away from the seating.

4. A pump for liquids as defined in claim 1 wherein the inlet passage and the outlet passage

are of a combined total length sufficient to insure, by the kinetic energy of the liquid flowing through said passages, the necessary pressure of flow of liquid upon the free and flexible portion of the diaphragm during the return stroke of the diaphragm to cause the said free and flexible portion to move away from the seating.

5. A pump for liquids comprising a pump casing; a pump chamber within said casing having spaced inlet and outlet passages, said passages being devoid of valves; a plurality of seatings within the pump chamber arranged in parallel spaced relation between the inlet and outlet passages; a plurality of reciprocable diaphragms disposed coaxially within the pump chamber between said inlet and outlet passages, each of said diaphragms adapted to cooperate with one of said seatings and to act as a combined piston and valve, said diaphragms dividing the pump chamber into a suction section in communication with the inlet passage and an outlet section in communication with the outlet passage, each of said diaphragms having a free and flexible peripheral portion adapted to engage its cooperating seating during the power strokes of the diaphragms when the diaphragms are drawing liquid into the suction section through the inlet passage and simultaneously forcing liquid from the outlet section through the outlet passage, and to move away from its cooperating seating during the return strokes of the diaphragms under the pressure of flow of the liquid through the pump to permit passage of the liquid from the suction section to the outlet section of the pump chamber; and means for simultaneously reciprocating said plurality of diaphragms.

6. A pump for liquids comprising a pump casing; a pair of separate and independent pump chambers disposed in axial alignment within said casing, each chamber having an inlet passage and an outlet passage, said passages being devoid of valves; a seating within each pump chamber between the inlet and outlet passages therein, the seatings in each of the pairs of chambers being disposed in opposite directions, a reciprocable diaphragm within each pump chamber between the inlet and outlet passages therein acting as a combined piston and valve and dividing each pump chamber into a suction section in communication with the inlet passage in the chamber and an outlet section in communication with the outlet passage in the chamber, each of said diaphragms having a free and flexible peripheral portion adapted to engage its cooperating seating during the power strokes of the diaphragms when said diaphragms are drawing liquid into the respective suction sections through the inlet passages and simultaneously forcing liquid from the respective outlet section through the outlet passages, and to move away from its cooperating seating during the return strokes of the diaphragms under the pressure of flow of the liquid through the pump to permit passage of the liquid from the respective suction sections to the respective outlet sections; a common operating spindle connected to each of the plurality of diaphragms for effecting alternate and successive power and return strokes to the diaphragms within the respective chambers of each pair of pump chambers whereby each pair of pump chambers and their cooperating diaphragms constitute a double-acting pump; and means for reciprocating said common operating spindle.

7. A pump for liquids comprising a pump casing; a pump chamber within said casing having

spaced inlet and outlet passages therein, said passages being devoid of valves; a plurality of spaced seatings within said chamber between said inlet and outlet passages; a plurality of spaced reciprocable diaphragms within said chamber between said inlet and outlet passages each acting as a combined piston and valve and said diaphragms dividing the pump chamber into a suction section at one side of the diaphragms in communication with the inlet passage and an outlet section at the opposite side of the diaphragms in communication with the outlet passage, each of said diaphragms having a free and flexible peripheral portion adapted to engage one of the seatings during the power strokes of the diaphragms when the diaphragms are drawing liquid into the suction section through the inlet passage and simultaneously forcing liquid from the outlet section through the outlet passage, and to move away from its cooperating seating during the return strokes of the diaphragms under the pressure of flow of liquid through the pump to permit passage of the liquid from the suction section to the outlet section; a common operating spindle connected to the plurality of diaphragms for effecting tandem operation of said diaphragms within said pump chamber; and means for reciprocating said common operating spindle.

8. A pump for liquids comprising a pump casing; a pump chamber within said casing having

spaced inlet and outlet passages, said passages being devoid of valves; a partition within said chamber between the inlet and outlet passages and having a plurality of openings therein; a plurality of reciprocable diaphragms within said chamber, one of said diaphragms overlying each of the openings in said partition and each acting as a combined piston and valve, said partition and diaphragms dividing the pump chamber into a suction section in communication with the inlet passage, and an outlet section in communication with the outlet passage, said diaphragms positioned on that side of said partition adjacent the outlet section of the chamber and each having a free and flexible peripheral portion adapted to engage a portion of the partition wall surrounding one of the openings in said partition during the power strokes of the diaphragms when said diaphragms are drawing liquid into the suction section through the inlet passage and simultaneously forcing liquid from the outlet section through the outlet passage, and to move away from said portion of said partition during the return strokes of said diaphragms under the pressure of flow of liquid through the pump to permit passage of the liquid through the openings in the partition from the suction section to the outlet section; and means for reciprocating said plurality of diaphragms.
